(57) **CLAIM**

A new, original, ornamental design for a nozzle for automobile painting, as shown and described.

DESCRIPTION

FIG. 1 is a perspective view of the nozzle for automobile painting having an inner body attached to an unclaimed external body;

FIG. 2 is a front view thereof, the back view being a mirror image thereof;

FIG. 3 is a left side view thereof, the right side view being a mirror image thereof;

FIG. 4 is a top view thereof;

FIG. 5 is a bottom view thereof;

FIG. 6 is a cross-section view through section A-A' of FIG. 4;

FIG. 7 is a perspective view of the nozzle for automobile painting detached from the unclaimed external body;

FIG. 8 is an enlarged top view of the inner body thereof;

FIG. 9 is an enlarged bottom view of the inner body thereof; and,

FIG. 10 is an enlarged left side view of the inner body thereof.

The broken lines in the drawings show an unclaimed external body of the nozzle for automobile painting and form no part of the claimed design.
